UNITED STATES PATENT OFFICE.

GEORGE E. WOODBURY, OF SAN FRANCISCO, CALIFORNIA.

BUTTER-BOX.

No. 838,832.

Specification of Letters Patent.

Patented Dec. 18, 1906.

Application filed December 1, 1904. Serial No. 235,047.

To all whom it may concern:

Be it known that I, GEORGE E. WOODBURY, a citizen of the United States, residing in the city and county of San Francisco and 5 State of California, have invented new and useful Improvements in Butter-Boxes, of which the following is a specification.

This invention relates to the production of an improved butter-box having the hinges 10 of the cover and other metal parts situated on and confined to the outside of the box and in the construction of which, and particularly of the hinges, provision is made for securing ample strength in the fastenings that join 15 the cover to the body to withstand careless handling during transportation and the quality of holding the cover in open position while the contents of the box are exposed 20 for sale in the store without being bent or 25 broken in the rough usage to which the box, and especially its cover, is subjected at such time.

The boxes used by the dairyman for sending table-butter to market in rolls or squares 25 are returned when empty to be again used for the same purpose; but before being filled again they are washed and cleansed by water or steam, particularly on the inside surfaces, to remove all contaminating agents or 30 diuims that might affect the flavor and other qualities of the butter. It becomes not only 35 desirous, therefore, to exclude all metal parts from the inside of the box, so that the same shall not be attacked and become 40 rusted by contact with the cleaning agents, but it is also highly important that no metal shall be in contact with or in close proximity 45 to the butter packed in the box, even though the package may be protected by wrappers, for the reason that the presence of the metal 50 parts in the same receptacle invariably results in affecting the delicate flavors and the loss of other qualities on the possession of which the market value of the article de- 55 pends.

The objects sought to be attained by the invention are to remove the metal parts that unite the cover to the box entirely from the butter-holding space of the body and to 55 sure such strength of parts that the cover will withstand the strains to which it is com- monly exposed, both during transportation and also while the cover is standing open.

To these ends and objects chiefly my in- 55 vention comprises a novel construction and

combination of a box provided with a rab- beted edge, a cover therefor, and metal parts producing an improved box for carrying butter and like substances and articles to market, as hereinafter described, and set 60 forth in the claim at the end of this specifi- cation, reference being had to the accom- panying drawings, in which—

Figure 1 is a view in perspective of one end 65 and a portion of a butter-box embodying my invention, the view including one end of the body and a portion of the cover standing in open position. Fig. 2 is a rear view, on an enlarged scale, of the hinge and part of the cover and the body of the box in which it is 70 fixed. Fig. 3 is a vertical section taken transversely through the body and the cover at one of the hinges, showing the cover closed. Fig. 4 is a similar view showing the cover 75 standing open. Figs. 5 and 6 represent in perspective the parts of the hinge detached from each other. Fig. 7 is a longitudinal 80 section through the hinge-joint, showing the parts as they stand when the cover is raised and turned back. Fig. 8 is an inverted plan 85 or bottom view of the knuckle of the top member, Fig. 5, of the hinge. Fig. 9 is an enlarged sectional view of the back of the cover and the top edge of the body on which the edge of the cover turns.

In the following description, *a b* indicate the sides and ends of the body *A* of the box, one end only being shown in Fig. 1, and *d* the bottom.

C is the cover, and *D* the hinges that unite 90 the cover to the body. The top edge of the body is formed with a rabbet 2, extending around the sides and ends, and the cover *C* is recessed to receive and fit closely over the narrow standing edge formed by the rabbet. 95 The rim 3 of the cover along the rear side is rounded on the bottom, as seen at 4, Figs. 1 and 9, so as to let the cover come to a square seat on the ledge 5 on the rabbeted top edge of the body when the cover is turned to stand upright, as well as to insure a close joint 100 between the cover and the body at the back when the cover is closed. The hinges *D* are set into this back rim, so that the knuckles 105 are flush with the surfaces of the box and the cover on the outside, and to that end the rim is made of about the same thickness as the dimension diametrically of the knuckles of the hinge. At those points in the length along 110 the back where the hinges are placed the rim

3 is cut away, as seen at 6 6, Figs. 1 and 2, to let in the knuckle of the hinge, and a slot or groove 7 in dimensions corresponding to the length, breadth, and thickness of one leaf 8 of the hinge is cut perpendicularly downward into the standing side of the box in line with the cut-away part 6 6 in the cover.

If the leaf 8 be made of semicircular outline, the time expended in cutting the grooves 10 in the body of the box will be greatly reduced, with a like effect in the cost of constructing and putting the parts together; but the principal object of this part of the construction is to remove this member of the hinge from 15 the butter-holding space and inclose it within the solid wood of the box. The remaining member of the hinge is attached to the cover by a relatively long strap 10, which is bent twice at right angles upon itself, so as to fit over 20 the back edge of the cover and lie upon the top on the outside. Giving the strap this shape brings it and the screws 12 13 on the outside of the cover, as seen in Figs. 3 and 4, with the effect to produce a strong fastening and a 25 stiff connection between the cover and the body of the box, as well as to remove these metal parts from the inside of the box. The screws set through the holes 14 in the strap and into, but not through, the cover, and the 30 screw inserted through the hole 15 and into the edge of the cover contributes materially to the strength and stiffness of the fastening. The screws 9 that fasten the leaf 8 of the hinge are inserted from the outside through 35 the screw-holes 16 in the leaf and set into the solid wood of the box.

As already described, the cover when turned upright is supported on the ledge at the back, on which it has a solid bearing; but 40 while that feature of the construction provides ample support for the cover, capable of resisting pressure that may be brought upon the cover from above and in the same plane, it will be seen that the application of a force 45 against the cover in a direction at right angles to the cover in its upright position tending to bend the cover back will act upon the hinge-joints and must be sustained by them. Provision is made, therefore, by a novel construction 50 of stop on one member of the hinge that will prevent the upper member of the hinge

from being bent back and take the angular strain off its knuckle at such time.

The construction and operation of this stop will be understood by references to Figs. 2, 5, 55 7, and 8, where it will be seen that the stop 7 is formed directly from the metal of the knuckle d' on the upper member of the hinge by cutting transversely through the knuckle from the lower side on two parallel lines and 60 then by a longitudinal cut separate the portion of severed metal along one side and finally bending that portion outward, so as to stand out beyond the circumference of the knuckle. When the cover is raised to the 65 upright position, the projecting end of the stop thus formed will strike against and be arrested by the leaf 8 instead of passing through the slot or open space between the two knuckles d^2 d^2 on the lower member, and 70 further movement in that direction with resulting strain on the knuckles is prevented. The relative position of the stop and part of the hinge when the cover stands upright is seen in Fig. 7. Any suitable locking means 75 may be provided for holding the box closed.

Having thus described my invention, what I claim, and desire to secure by Letters Patent, is—

The combination of a box having a rabbeted 80 edge, a cover constructed to fit the rabbeted edge of the box, there being formed in one side, A, of the box a slot 7 extending downward from the rabbet, and a hinge for uniting the cover and the box having a leaf or part 8 85 adapted to enter the said slot 7 and be secured therein, and formed at its upper end with the knuckles d^2 which lie in the rabbeted portion of the box, and another part 10 substantially L-shaped secured to the box-cover and 90 formed with the knuckle d' , adapted to be connected with the knuckles d^2 of the part 8, one of the parts of the hinge being provided with a stop 17, substantially as set forth.

In testimony whereof I have hereunto set 95 my name to this specification in the presence of two subscribing witnesses.

GEORGE E. WOODBURY.
